RIBBON-RUN TRIMMING

Mary Ina Walden, Castle Rock, Wash.

Application October 1, 1949, Serial No. 5,251

Term of patent 14 years

(Cl. D3—32)

To all whom it may concern:

Be it known that I, Mary Ina Walden, a citizen of the United States and a resident of Castle Rock, in the county of Cowlitz, State of Washington, have invented a new, original, and ornamental Design for Ribbon-Run Trimming, of which the following is a specification, reference being had to the accompanying drawings, forming a part thereof.

In the drawings:

I claim:

The ornamental design for a ribbon-run trimming, as shown and described.

MARY INA WALDEN.
